Primary Examiner — Melanie H Tung*Assistant Examiner* — Bao-Yen Nguyen(74) *Attorney, Agent, or Firm* — NSIP Law**CLAIM**

I claim the ornamental design for a display screen or portion thereof with graphical user interface, as shown and described.

DESCRIPTION

The sole FIGURE is a front view of a display screen or portion thereof with graphical user interface, showing my new design.

The broken lines illustrate the display screen or portion thereof and form no part of the claimed design.

1 Claim, 1 Drawing Sheet(56)
